UNITED STATES PATENT OFFICE.

KONRAD JAGSCHITZ, OF MAINZ, GERMANY, ASSIGNEE TO MASCHINENFAERIK AUGSBURG-NUREMBERG A. G., OF NUREMBERG, BAVARIA, GERMANY, A CORPORATION OF GERMANY.

SEALING MEANS FOR GAS HOLDERS.

Application filed April 19, 1921. Serial No. 462,739.

To all whom it may concern:

Be it known that I, KONRAD JAGSCHITZ, a citizen of Austria, and resident of Mainz, Germany, have invented certain new and useful Improvements in Sealing Means for Gas Holders, of which the following is a specification.

My present invention consists in an improvement in sealing means for gas holders, of which seal several forms are described and illustrated in my earlier Letters Patent 1,275,696, dated July 31st, 1914.

The improved seal is constructed according to the present invention by arranging in the annular peripheral trough containing the sealing fluid, a sealing means or packing consisting of a material that is sufficiently impervious to liquid. The inner edge of this sealing means is attached in a liquid-tight manner to the closing member, whereas its outer edge is attached in a fluid-tight manner to a sealing member which is adapted to slide in a fluid-tight manner on the inner wall of the holder, and which is pressed against the inner surface of the holder by means of suitable weighted levers or spring-actuated levers. This sealing member is preferably made of iron, wood, leather, or the like.

A constructional example of the improved seal is illustrated in the accompanying drawing in which Fig. 1 is a vertical section through the sealing means and the adjacent parts of the wall of the holder and the closing member; Fig. 2 is a vertical section illustrating another form of the invention.

a is the wall of the gas holder in which the disk shaped closure member *b* is vertically movable. The periphery of said closure member *b* is shaped to form a trough *c* which contains the sealing fluid and extends about the entire periphery of the disk shaped closure member *b*. A packing supporting member *f* extending continuously through the entire annular peripheral trough *c* and composed of material that is impervious to fluid, is attached at its inner edge in a liquid-tight manner to the closure member *b*, whereas at its outer edge it is attached in a fluid-tight manner to the sealing member or packing *d* which is adapted to slide on the inner surface of the wall of the holder. The sealing member or packing *d* which is adapted to slide on the wall of the holder is connected at suitable distances apart to

weighted levers *e*, which are pivoted at *g* and thus effect a pressing of the sealing member *d* against the holder wall to seal the space between the trough and the wall of the holder.

Spring-actuated levers may be employed instead of these weighted levers, as shown in Fig. 2.

I claim:

1. The combination of a gas holder, a closure member movable therein, an annular peripheral trough carried by said closure member and slidable along the inner surface of said gas holder, said trough being adapted to contain a sealing fluid, a sealing member impervious to liquids located in said trough and slidable along said inner surface of said gas holder, a packing supporting member having its inner edge connected with said closure member in a fluid-tight manner and its outer edge connected with said sealing member in a fluid-tight manner, and mechanical means carried by said closure member and exerting a force in a direction solely transverse to the direction of movement of said closure member for automatically pressing said sealing member into close contact with said inner surface of the gas holder to thereby provide a fluid-tight joint without obstructing the sliding movements of said sealing member.

2. The combination of a gas holder, a closure member movable therein, an annular peripheral trough carried by said closure member and slidable along the inner surface of said gas holder, said trough being adapted to contain a sealing fluid, a sealing member carried by said closure member and located in said trough and slidable along the inner surface of said gas holder, a lever pivotally mounted upon said closure member and operatively connected with said sealing member, and a weight carried by said lever whereby the latter is actuated to press said sealing member into surface contact with said inner surface of the gas holder to provide a fluid-tight joint without obstructing the sliding movements of said sealing member.

3. The combination of a gas holder, a closure member movable therein, an annular peripheral trough carried by said closure member and slidable along the inner surface of said gas holder, said trough being adapted to contain a sealing fluid, a sealing

member carried by said closure member and located in said trough and slidably along the inner surface of said gas holder, a lever pivotally mounted upon said closure member and operatively connected with said sealing member, and means connected with said lever whereby the latter is actuated to press said sealing member into surface contact with said inner surface of the gas holder to provide a fluid-tight joint without obstructing the sliding movements of said sealing member.

In testimony whereof I have hereunto set my hand in the presence of two subscribing witnesses.

KONRAD JAGSCHITZ.
